(57) **CLAIM**

The ornamental design for a ferrule for optical connectors, as shown and described.

DESCRIPTION

FIG. 1 is a top, front perspective view of a ferrule for optical connectors;

FIG. 2 is a bottom, rear perspective view thereof;

FIG. 3 is a front view of thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown in the drawings illustrate portions of the ferrule for optical connectors that form no part of the claimed design.

The dot-dash broken lines in the drawings represent boundaries that form no part of the claimed design.

The shading and contour lines on the surfaces of the ferrule for optical connectors show contour and not surface ornamentation.
